EDWARD M. LYNCH, OF ST. LOUIS, MISSOURI, ASSIGNOR OF ONE-THIRD TO WHITSON
C. BUCK AND ONE-THIRD TO HUMPHREY A. BUCK, BOTH OF ST. LOUIS, MISSOURI.

SUPPLEMENTARY AIR-SUPPLYING DEVICE FOR AUTOMOBILE-ENGINES AND THE LIKE.

1,117,682.

Specification of Letters Patent.

Patented Nov. 17, 1914.

Application filed July 14, 1913. Serial No. 778,841.

To all whom it may concern:

Be it known that I, EDWARD M. LYNCH, a citizen of the United States, residing at the city of St. Louis, State of Missouri, 5 have invented certain new and useful Improvements in Supplementary Air-Supplying Devices for Automobile-Engines and the like, of which the following is a specification, reference being had therein to the accompanying drawings.

This invention relates to certain new and useful improvements in supplementary air-supplying devices for automobile engines, of the type adapted to supply a supplementary amount of air to the mixture of air and gasoline that is drawn from the carburetor to the cylinders of an automobile engine or the like.

The primary object of the invention is to 20 provide improved means for supplying a supplementary quantity of air to the combustible mixture, which means is of simple and economical construction, and which also serves to allow cleaning of the engine 25 cylinders by the introduction into the latter of kerosene for the purpose of burning out the carbon deposits in the latter, thus obviating the necessity of removing the spark plugs and other parts when the cylinder or cylinders are to be cleaned.

In the drawings: Figure 1 is a side elevation of the invention applied to a manifold; Fig. 2 is an enlarged top plan view of the invention, the manifold being shown 35 in fragmentary section; Fig. 3 is a section taken on the line 3—3 of Fig. 2; and Fig. 4 is a detail view, in perspective, of the valve and its stem.

The invention consists of a device which 40 is secured or attached to the manifold intermediate the carburetor and the cylinders, as depicted in Fig. 1, which device embodies a casing 1 that has its inner end 2 reduced and exteriorly threaded and engaged with a threaded opening 3 formed in a side wall 45 of the manifold 3'. The peripheral contour of the casing is preferably angular, such as hexagonal, to receive a wrench or the like to allow the casing to be securely 50 threaded into engagement with the manifold. The outer end of the casing is reduced at 4 and has a smooth cylindrical surface which latter is engaged by the inner circumference of an annular flange 6 of

a cap or nut 5 that slides on the periphery 55 of the reduced outer end 4. The outer end of the cap 5 is closed and is provided with a central opening which is threaded and which receives the threaded outer end portion 7 of the valve stem 8. The inner extremity of the stem 8 has a conical valve 9 formed thereon which engages in a valve seat 10 formed on the inner end of the casing 1. The casing 1 has a bore 11 which extends through the inner end of the casing 15 and a chambered portion 12 which extends through the outer end of the casing, the valve stem being received in the bore and chambered portions as illustrated in Fig. 3 of the drawings. The valve stem 8 70 is flattened on one or more sides at 13 and is surrounded by a coil spring 14 which latter at one end extends within the flange 6 of the cap 5 and at its opposite end abuts the shoulder 15 which is formed by the inner end of the chambered portion 12, whereby it will be seen that the spring holds the valve 9 in its seat 10 as depicted in Fig. 3 of the drawings.

A funnel 16 is attached to the casing 1 80 in an upright position and serves not only as an air inlet, but also as a means whereby kerosene may be poured into the casing for a purpose now to be set forth.

In operation, the suction in the engine 85 cylinder, causes the valve 9 to open inwardly with the result that a quantity of air enters funnel 16, and passes through bore 11 in the space between the walls of said bore and the flattened part or parts 13 90 of the valve stem into the manifold. The air drawn into the manifold as just described dilutes the mixture of air and gasoline from the carburetor C, so that when the charge is fired it expands with greater pressure and thus not only increases the speed 95 of the engine, but also allows the latter to be run with use of less gasoline and thereby effects saving in the expense of fuel. By adjusting the cap 5 on the valve-stem 8 the 100 tension of the spring may be regulated to permit the quantity of air that enters the manifold to be regulated or governed, as desired.

When cleaning of the engine cylinders is 105 to be effected, the cup or funnel 16 is filled with kerosene, which latter is drawn into the cylinders upon the suction stroke of the

piston, and which burns out any carbon deposits, thus eliminating the removal of the spark-plugs and other parts when the cleaning operation is to be effected.

5 What is claimed is:

In a device of the type set forth, a valve casing having a reduced exteriorly threaded inner end, a valve seat on the inner extremity of the casing, the outer end of the 10 casing having a smooth periphery of circular cross-section, said casing having a bore which extends through its inner end and a chambered portion which extends through its outer end and forms a shoulder at the point of juncture with the inner 15 end of the bore, a valve engaged with said seat and having its stem flattened in part and extending through the bore and cham-

bered portion of the casing and having its outer end threaded and extending beyond the outer end of the casing, a spring 20 circling the stem and engaged at one end with said shoulder, a cap threaded on the stem and having a flange that slidingly engages over the said outer end of the casing, 25 the other end of the spring extending within the flange of the cap and abutting the closed end of the latter, and a funnel on the casing in communication with the chamber thereof.

In testimony whereof I hereunto affix my signature in the presence of two witnesses.

EDWARD M. LYNCH.
